UNITED STATES PATENT OFFICE.

SAMUEL J. SEELY, OF NEW YORK, N. Y.

CANAL-LOCK GATE.

Specification of Letters Patent No. 18,555, dated November 3, 1857.

To all whom it may concern:

Be it known that I, SAMUEL J. SEELY, of the city, county, and State of New York, have invented certain new and useful Improvements in Canal-Lock Gates; and I do hereby declare that the following is a full, clear, and exact description thereof, reference being had to the accompanying drawings, making part of this specification, in which—

Figure 1 is a plan of a canal lock with a gate on my improved plan; Fig. 2 an elevation of one of the flaps of the gate; Fig. 3 a vertical section taken at the line A of Fig. 1; Fig. 4 another section taken at the line B, b of Fig 1; and Fig. 5 a plan representing a modification.

The same letters indicate like parts in all the figures.

As canal lock gates are generally constructed and hung it is found necessary to balance them by a heavy beam projecting outward from the hinge post and opposite to each flap of the gate. This adds greatly to the weight and consequently to the friction of the gate, and obstructs the passage around the gate. It is also necessary to have a separate foot bridge across the lock which is expensive and inconvenient; and the wicket gates are too liable to leak and are otherwise defective. But the most serious objection to the mode of construction in general use is to be found in the fact that the two flaps have to be operated separately for opening and closing, and require from four to six men to work them, and even with that amount of power the operation is very slow; and from the want of adequate control the gates are liable to serious injury from slamming when the lock tenders are at all negligent. These defects I have fully remedied by my invention as proved by the test of experiment. And the first part of my said invention consists in connecting the journal at the upper end of the hinge post of each flap of the gate with the masonry of the lock by means of a journal box connected by an adjusting screw, or equivalent means, with a plate firmly secured to the masonry, so that the swinging of each flap of the gate can be readily adjusted, and the weight sustained without the necessity of a balance beam. And the second part of my said invention consists in suspending the outer or swinging edge of each flap of the gate to the upper journal box by a diagonal suspension

brace provided with suitable means for cambering the frame work from the journal box. And the third part of my said invention consists in connecting the two flaps of the lock gate by a joint link and arm, or equivalent means, so that the two shall move simultaneously in opening or closing, when this is combined with a connection of the said gate with a capstan at the side of the lock, so that the gate can be opened or closed from one position and with better control of the gate than by any other plan before known.

In the accompanying drawings (a, a) represent the two flaps of the gate constructed in the usual manner so far as regards the frame work, and, as the appendages of both flaps are alike, the description of one will answer for both. The lower end of the hinge post (b) is provided with a metallic plate and semi-spherical pivot (c) fitted to a metallic step (d) properly secured in the masonry work of the lock. The upper end of the said post is properly formed to receive a metal plate (e) with a surrounding flange, which plate is there secured by screws or other suitable means. And from the top of this plate projects a central journal (f) which turns freely but accurately in the central hole of the lower plate (g) of a friction box. A wing (h) projecting from the edge of the plate (g), is fitted to slide in suitable ways (i, i) on the top of a plate (j) let into, and firmly secured to the coping of the masonry work of the lock. The wing of the plate (g) and the plate (j) are connected, as represented, by an adjusting screw (k) by means of which the plate (g) with the journal of the gate flap can be moved in and out at pleasure to adjust the gate to its required position in the lock. And with the view to accuracy of adjustment the line of motion of the sliding wing of the plate (g) should be in the plane of the gate flap when closed. The better to secure the plate (g) screws (l, l) pass through elongated holes in the wing (h) and are tapped in the plate (j). Over the lower plate (g) of the friction box is fitted the upper or cap plate (m) of the said box, which said plate is also fitted to the journal (f), and provided with a cylindrical flange which fits snugly over the periphery of the lower plate, and the inner surface of these two plates have corresponding annular grooves to receive friction balls (n), or these surfaces may be

otherwise adapted to reduce the friction due to the weight which they have to sustain.

The upper part of the cap plate is formed with a bracket piece (*o*) through which 5 passes one part of a diagonal suspension brace rod (*p*), which has a head on the upper end and a thread cut on the lower end to receive the nut of the swivel link (*q*) by which it is connected with the lower part of 10 the suspension brace rod. By this means the outer edge of the gate flap is suspended to the friction box of the journal on the upper end of the hinge post, and as the friction box is connected by the sliding wing and ad- 15 justing screw with the plate secured in the masonry of the lock, the whole is firmly sustained without the necessity of a balance beam. The sum of the weight to be sus- 20 tained is greatly reduced, as also the fric- 25 tion, and much room is saved, while at the same time the hinge post can be readily ad- justed to its socket in the masonry by the 30 adjusting screw which connects the friction box with the plate secured to the masonry, 35 and the frame work of the gate can be readily cambered by simply turning the link nut on the diagonal suspension brace rod.

To the upper edge of one of the flaps of the gate is hinged one end of a cogged rack 30 bar (*r*) which passes through a slot in the base plate (*s*) of a capstan, the said base plate being let into and firmly secured to the mason work of the lock. The capstan (*t*), which may be of any suitable construc- 35 tion, is provided with a pinion at the lower end to engage the cogs of the rack bar, so that by turning the capstan the gate flap will be readily opened and closed, and will be at all times under the control of the lock 40 tender who will be able not only to give the required motions with much greater ease than heretofore but will be able to avoid all injurious slam in closing. That flap of the gate which is connected with the capstan by 45 the rack rod is provided with an arm (*u*) placed either near the lower, or the upper edge, and the outer end of this arm is con- 50 nected by a joint link (*v*) with the other flap of the gate, so that the movements of one flap will impart a corresponding move- 55 ment to the other. In this way the entire gate can be readily and efficiently either opened or closed by the simple turning of the capstan.

55 Instead of the rack bar and linked arms, I propose as an equivalent to form the connection of the two flaps with each other and with the capstan by means of a chain as represented by red lines in Fig. 5 in which said 60 figure the chain (*a*²) is represented as at- tached to the outside of one of the flaps (*a*) of the gate, passes around a sprocket wheel (*b*²) on the lower end of the capstan (*t*) thence over a guide pulley (*c*²) at the upper 65 edge of the wall, down to and around an-

other guide pulley (*d*²) at the bottom, and thence to the inside of the other flap of the gate to which it is attached. Another chain (*e*²) is attached to, and forms a connection with the two flaps of the gate in same manner as chain (*a*²), but in the reversed direction, and, instead of passing around a sprocket wheel on a capstan as the first chain, simply passes around a guide wheel (*f*²) occupying the same relative position. 70 From this it will be seen that by turning the capstan in one direction both flaps of the gate will be opened simultaneously, and by turning it in the opposite direction both flaps will be closed, thus putting the gate 80 entirely within the control of the capstan. A platform (*w*) with a railing (*x*) is se- 85 cured by legs (*y*) to the upper edge of each of the flaps so that when the gate is closed the two platforms will form a foot bridge across the lock which bridge will however be opened and permit the free passage of tow lines when the gate is open.

The wicket gates (*a*', *a*') are formed each in the segment of a hollow cylinder, and the 90 ends (*b*', *b*') in the form of sectors with the journals projecting therefrom, and fitted to suitable boxes. To the inner journals of the 95 two wickets is secured a sector pinion (*c*') the cogs of which are engaged by the cogs of a vertically sliding rack bar (*d*'), provided with another set of rack teeth near the upper end which are engaged by a sector pinion (*e*') so that by means of a hand lever or hand spike (*f*') the two wickets can be 100 readily opened and closed.

On one side the lower edge of the open- 105 ings, in which the wicket gates are placed, is curved out to correspond with the circular form of the wickets, and on the other side the edge of the said openings is beveled and 110 on this beveled surface is secured to each opening a metal plate (*g*') with india rubber or equivalent elastic packing interposed, the edge of the said packing projecting so as to make a packed joint with the peripher- 115 ery of each of the wickets. And the upper edge of each opening is also packed in the same manner with a strip of india rubber or equivalent elastic packing held in place by a metal plate so that in closing the wickets their upper edges shall come in contact with the elastic packing and thus effec- 120 tually shut out the water.

Having thus fully described the mode of 120 construction which I have applied with suc- cess I do not wish to be understood as limit- 125 ing my claim of invention to the special form specified, but claim the privilege of modifying the same so long as I attain the same end by means substantially the same.

What I claim as my invention and desire to secure by Letters Patent is—

1. The method, substantially as herein specified of connecting the upper journals 130

of canal lock gates to the masonry of the lock by means of adjustable boxes substantially as and for the purpose specified.

2. I also claim suspending the outer or swing edges of the gate to the upper journal boxes by diagonal suspension braces, in the manner and for the purpose, substantially as specified.

3. I also claim connecting the two flaps of the gate with each other so that the two shall move together by means of the joint

link and arm, or other equivalent means substantially as described, in combination with the connection with a capstan at the side of the lock by a jointed rack or other equivalent means, substantially as described and for the purpose set forth.

SAML J. SEELY.
